UNITED STATES PATENT OFFICE.

ERNEST SCHIMALE, OF BELLEVILLE, ILLINOIS, ASSIGNOR TO BELLEVILLE STOVE AND RANGE COMPANY, OF BELLEVILLE, ILLINOIS.

DOOR AND FRAME CONSTRUCTION.

Application filed September 20, 1922. Serial No. 589,430.

To all whom it may concern:

Be it known that I, ERNEST SCHIMALE, a citizen of the United States, and a resident of Belleville, in the county of St. Clair and State of Illinois, have invented certain new and useful Improvements in Door and Frame Constructions, of which the following is a specification.

An object of my invention is to provide 10 a door and frame construction which is adapted to be provided in a casing, such as the casing forming an oven compartment of a stove, and which includes readily operable means of simplified construction 15 which permit or prevent access to the interior of the casing, as desired.

A further object of my invention is to provide a door and frame construction of the character described in which the door 20 will normally be maintained in either a determined open position or closed position and will swing automatically to closed position when moved slightly in the direction thereof from the open position.

25 Other objects and advantages will be apparent from the following description, and the novel features of the invention will be particularly outlined in the appended claims.

30 My invention is illustrated in the accompanying drawings, forming a part of this application, in which

Figure 1 is a perspective view of a casing equipped with my invention,

35 Figure 2 is a relatively enlarged vertical section through the structure shown in Figure 1,

Figure 3 is a fragmentary perspective group view showing one lower corner portion of a door comprised in the device and a latch member adapted to be associated therewith together with means for securing the latch member to the door, and

40 Figure 4 is a view similar to Figure 3 showing the other lower corner portion of the door together with the elements adapted to be associated therewith.

45 Figure 5 is a perspective view of one of the bearing caps comprised in the construction.

50 Referring now to the drawings, I show a practical embodiment of the invention provided with a casing 1 which in the present instance is the casing of the oven portion of a stove but which may be the casing of

any suitable container or structure. One of the vertical walls of the casing 1, preferably the front wall, is provided with a plurality of openings 2, there being an opening for each compartment provided within the casing 1. In the present instance, two openings 2 are provided, one being positioned above the other and being of greater area than the other. The openings 2 are margined by frames 3 which may be integral portions of the front wall of the casing 1. In the drawings, the frames 3 are shown as having the longitudinally extending intermediate portions of the horizontal members thereof arcuate in cross sectional 70 contour as indicated at 4 in Figure 2 and being curved outwardly from flat vertically extending inner edge portions 5 which constitute seats for doors 7, the doors 7 being swingingly supported upon the frames in 75 a manner which will be hereinafter described. The lower horizontal member of the upper frame 3 is also the upper horizontal member of the lower frame 3 in the casing 80 illustrated.

Each of the doors 7 is provided with a pair of oppositely extending trunnions 8 at the lower corners thereof, which trunnions are slightly offset downwardly in respect to the plane of the lower end of the door proper. The trunnions 8 of each door are journaled in openings or notches 9 provided in the proximate sides of hollow bearing caps 10 which are supported upon the vertical side members of each 90 frame 3 at the lower ends of the latter. Each bearing cap 10 is of channelled formation and is enlarged laterally intermediate of its length. An offset lug 11 extends from the one end of each bearing cap 10 and 95 is adapted to be inserted in one of the vertical slots 12 formed in the vertical side members of each frame 3 at the lower ends thereof so that the lug 11 will engage with the inner wall of the said one of the vertical members of the frame 3 at the upper end of the slot 12 therein and the bearing cap will thus be secured in position on one of the frames 3 when a screw is projected through a screw receiving opening 13 in the 100 lower end of a bearing cap and into engagement with the underlying portion of one of the frames 3. With the organization described in which the bearing caps 10 are arranged in pairs, there being a pair of 110

bearing caps at the lower end of each frame 3, the doors 7 will be swingingly supported at their lower ends and may be swung upwardly against the seats 5 or 5 downwardly from the position shown in Figure 1 and in the upper part of the structure shown in Figure 2 to open position as illustrated by the position of the lower door in Figure 2.

10 The trunnions 8 are provided with non-circular end portions 14 which extend through the notches 9 into the bearing caps 10. A latch element 15 has a central opening 16 of non-circular contour and adapted 15 to receive the non-circular end portion 14 of one of the trunnions 8, whereby the latch member 15 will be supported on the portion 14 of the trunnion to rotate with the latter and against rotation independently of 20 the trunnion. The latching element or member 15 may be removably secured on the non-circular portion of one of the trunnions by means of a locking cap 17 held 25 against the outer face of the latching member by a screw 18 extending through the locking cap into engagement with a threaded axial opening or socket 19 in the non-circular portion 14 of one of the trunnions. The edge of the locking cap 17 that is held 30 in contiguous relation with the latching member 15 is serrated as indicated at 21 to engage with the latching member and thus be held against rotation independently of the latter.

35 The latching member 15 is in the form of a disk having a projection or nose 22 extending radially from the periphery thereof, which nose portion is adapted to bear upon and engage a horizontal stop shoulder 23 40 provided on the inner wall of one of the bearing caps 10 when the door of which the trunnion 8 carrying the latching member 15 is a part has been swung downwardly from vertical or closed position into horizontal position.

45 Each of the doors 7 is provided with two latching elements, there being a latching element secured to each of the trunnions 8 of the door. The latching element 15 which 50 has been described is mounted on one of the trunnions 8 as described and a latching element 24 is mounted upon the other trunnion 8 of each door. Each latching element 24 comprises a head 25 that is similar to the 55 latching member 15 and is formed with a non-circular opening 26 receiving the non-circular end portion 14 of one of the trunnions 8. The latching member 24 is held 60 on one of the trunnions 8 through the agency of one of the locking caps 17 and one of the screws 18 in conjunction with the threaded axial opening or socket 19 in the end of the trunnion. The head portion 25 of the latching element 24 also includes a nose portion 65 or projection 27 on the periphery there-

of, which projection is substantially identical with the projection 22 of the latching element 15 and is positioned in horizontal alignment therewith. The latching member 24 differs from the latching member 15 in 70 that it includes an arm portion 28 which extends radially thereof. The arm portion 28 is adapted at its outer end to interfit a groove 29 in the one face of a longitudinal weight 30 and is secured to the latter by 75 means of screws 31 or the like.

80 From the foregoing description of the various parts of the device, the operation may be readily understood. The arm 28 of each latching member 24 extends through one of the slots 12 into the interior of the casing 1. The peripheral portions of each of the latching members 15 also projects into one of the slots 12. The angular relation of the arm 28 to the nose portion 27 of 85 each latching member 24 is such that the door provided with one of the weighted latching members 24 will be actuated by gravity to swing to closed position when moved slightly from horizontal or open position. The center of gravity of the weight 30 carried by each arm 28 lies in a vertical plane when the door to which the latching member 24 is attached is horizontally disposed and in consequence, the doors 7 will 90 be maintained by their own weight in horizontal or open position when moved thereto but will be instantly swung to closed position by actuation of the gravity controlled weighted arms 28 when the doors are swung 95 upwardly slightly from horizontal or fully opened position. The nose portion 27 and 100 22 of the respective latching members carried by each of the doors 7 will engage with the horizontal shoulders 23 of the bearing 105 caps associated with each door when such door has been swung to horizontal position and will prevent further downward swinging movement of the door.

110 The doors 7 have been shown as provided with handles 32 adapted to be grasped to conveniently operate the doors.

115 Obviously, my invention is susceptible of embodiment in forms other than that illustrated in the accompanying drawings and I therefore consider as my own, all modifications and adaptations thereof which fairly fall within the scope of the appended claims.

120 I claim:

1. In a door and frame construction, a vertically disposed frame having an opening therein, said frame having vertical slots in the side portions thereof adjacent to the lower end of the opening, a door having trunnions extending in axial alignment with respect to each other from the lower corner portions thereof, bearing caps adapted to be attached to said frame in position to cover the vertical slots in the latter and having 125 130

- notches in their proximate walls through which the trunnions may extend, said bearing caps having horizontal shoulders on their inner walls, latch members secured to the end portions of said trunnions and being housed in said bearing caps, said latch members having projecting portions on the periphery thereof adapted to engage the horizontal shoulders of the bearing caps when the door has been swung downwardly to horizontal position, and an arm extending from one of said latching members through one of said slots and being weighted at its end remote from the latching member.
- 5 2. In a door and frame construction, a vertically disposed frame having an opening therein, said frame having vertical slots in the side portions thereof adjacent to the lower end of the opening, a door having 10 trunnions extending in axial alinement with respect to each other from the lower corner portions thereof, bearing caps adapted to be attached to said frame in position to cover the vertical slots in the latter and having notches in their proximate walls through which the trunnions may extend, said bearing caps having horizontal shoulders on their inner walls, latch members secured to the end portions of said trunnions and being housed in said bearing caps, said latch members having projecting portions on the periphery thereof adapted to engage the horizontal shoulders of the bearing caps when the door has been swung downwardly to horizontal position, an arm extending from one of said latching members through one of said slots and being weighted at its end remote from the latching member, and a longitudinal weight carried by said arm and disposed in angular relation to the projection 15 on the latching member so that the center of gravity of said weight will lie in a plane perpendicular to the plane of the door when the latter is horizontally disposed.
- 20

ERNEST SCHMALE.
